UNITED STATES PATENT OFFICE

2,637,501

MINIATURE OR TOY RAILROAD TRACK

Harold L. Joyce, Hartford City, Ind.

Application January 27, 1947, Serial No. 724,647

9 Claims. (Cl. 238—10)

1

The invention relates generally to a miniature or toy railroad track, particularly adapted for electrically operated miniature trains.

The invention has among its objects the production of a miniature track, which may be of two-rail construction, in which the rails are electrically insulated from one another, whereby they may act as separate electrical conductors, and in which the ties are integrally connected in the form of relatively long strips to which the respective rails are attached, at the same time giving the appearance of a plurality of individual railway ties.

Another object of the invention is the production of such a track which is very simple in construction, and which may consist of only three pieces, the two rails and the tie strip or base member upon which the rails are carried, the construction being particularly adapted for tracks of very small gauge.

A further object of the invention is the production of such a track in which the same rails and tie base, or strips, may be employed, as desired, for either straight or curved sections of track, and which possesses considerable strength insofar as deformation or breakage is concerned.

Many other objects and advantages of the construction herein shown and described will be obvious to those skilled in the art from the disclosure herein given.

To this end my invention consists in the novel construction, arrangement and combination of parts herein shown and described, and more particularly pointed out in the appended claims.

In the drawings, wherein like reference characters indicate like or corresponding parts:

Fig. 1 is a top plan view of the straight section of the track embodying the present invention;

Fig. 2 is a view similar to Fig. 1, illustrating a curved section of track;

Fig. 3 is a sectional view taken approximately on the line 3—3 of Fig. 1;

Fig. 4 is a sectional view taken approximately on the line 4—4 of Fig. 3, and

Fig. 5 is a perspective view of a modified form of rail that may be used with the present invention.

In the past it has been difficult to produce a miniature railway track, for use with scale models or the like, which possesses a realistic appearance, and at the same time is simple in construction, having a minimum of parts, and is relatively inexpensive to manufacture. This is particularly true with the smaller models, as it becomes increasingly difficult to provide a realistic

track of very small size. For example, the present invention is particularly adapted for use on track having a gauge of $\frac{1}{2}''$ or less, in which construction the scale width of the ties would be approximately $\frac{1}{8}''$ of an inch. Obviously, while it is possible with larger gauge track to employ individual ties, as has been done, it becomes impractical to do so in such small gauge track. Similarly, even in larger gauge track, wherein individual ties have been utilized in the past, considerable work in the initial construction of the track may be required due to the numerous pieces employed, and which may become separated from the rails and lost.

As most of the miniature trains, at the present time, are electrically operated, it is particularly desirable that the supporting structure for the rails be of an insulated material, whereby the rails may be used as separate electrical conductors.

Referring to the drawings, 1 indicates generally a strip of plastic or other suitable material having good electrical insulation characteristics, which is corrugated throughout its length, as clearly illustrated in Fig. 4, forming raised ties 2, each being of an inverted U-shape in cross-section, comprising a top wall 3 and side walls 4, the latter downwardly diverging and adjacent walls connected by a bottom or base portion 5.

As illustrated in Figs. 1 and 3, each tie 2 has a pair of slots 6 and 7 respectively, extending substantially through walls 3 and 4 of the tie, the slots 6 and the slots 7, respectively, in the various ties being longitudinally aligned with one another, with the respective slots 6 extending parallel to the slots 7. Carried by the strip 1 are a pair of rails indicated generally by the numeral 8, each of which, in the construction illustrated in Figs. 1 and 3, consists of a head 9 and flange 11, connected by a web 12, similarly to the usual railroad rail but on a much reduced scale.

Extending vertically downward from the bottom of the flange 11 of each rail is a longitudinally extending strip or flange 13 of a thickness to closely engage the respective slots 6 and 7, whereby when the rails are positioned as illustrated in Figs. 1 and 3, with the strips 13 positioned in the slots, the bottom edges 14 of the strips 13 will seat upon the upper surfaces of the base portions 5, the adjacent edges 15 and 16 of the walls 4 of the ties 2, and the edges 17 and 18 in the top walls 3 of the respective ties will frictionally engage the side faces of the flanges

13 of the rails, thereby maintaining the same in operative position.

The rails 8 illustrated may be formed in any suitable manner, as for example, by extrusion. However, if desired, the flange 11 may be omitted from the rail, as illustrated in Fig. 5, wherein the rail 8' is provided with a head 9', web 12' and flange portion 13'. The only difference between the two rails is the elimination of the flange 11, the dimensions of the rails being such that either 10 may be used with the strip.

The strip 1 is of sufficiently light material that it may be flexed slightly when it is desired to form a curved section of track, as illustrated in Fig. 2, the corrugated construction permitting 15 the tie portions to expand slightly adjacent the outer edge thereof. It will be noted that the bottom surface 14 of the rail seats at all times upon the base portions 5 intermediate the respective tie portions; consequently, the track is 20 extremely strong for its size. For example, a person may stand on a track of $\frac{1}{2}$ " gauge without damage to either the rail or the relatively light plastic strip 1. Similarly, as the rail is at 25 all times resting on the base portions 5, the head 9 will be positioned at a uniform height, whether the track is straight or curved.

While I have shown the strip or flange 13 as being continuous, obviously a series of spaced flanges could be employed in cooperation with slotted ties at similarly spaced intervals.

Having thus described my invention, it is obvious that various immaterial modifications may be made in the same without departing from the spirit of my invention; hence, I do not wish to be understood as limiting myself to the exact form, construction, arrangement and combination of parts herein shown and described, or uses mentioned.

What I claim as new and desire to secure by Letters Patent is:

1. In a miniature or toy railroad track, the combination of a tie strip of relatively thin electrical insulating material, having a series of transverse corrugations therein, simulating spaced ties connected by base portions, the width of each base portion being less than the width of said tie portions, the latter having downwardly diverging side walls, said tie portions each having a pair of spaced parallel slots therein extending transversely substantially therethrough, with the separated sections, so formed, of each tie connected by the adjacent base portions, corresponding slots in the respective tie portions being longitudinally aligned, and a rail member positioned in each series of longitudinally aligned slots, with the bottom edges of said rail members resting substantially on the respective base portions and supported therefrom, the width of said slots being such that the rail members are frictionally engaged by the adjacent edges of said tie sections, the track so formed being sufficiently flexible to permit curving thereof when desired, whereby the same may be employed either as straight or curved track.

2. In a miniature or toy railroad track, the combination of a tie strip, of relatively thin electrical insulating material, having a series of transverse corrugations therein, simulating spaced ties formed with laterally spaced slots, a plurality of parallel rail members supported by said strip and adapted to frictionally engage the slots of the ties, said strip and said rails being sufficiently flexible to permit curving there-

of when desired, whereby the same may be employed either as straight or curved track.

3. In a miniature or toy railroad track, the combination of a tie strip of relatively thin electrical insulating material, having a series of transverse corrugations therein, simulating spaced ties connected by base portions, the width of each base portion being less than the width of said tie portions, the latter having downwardly diverging side walls, said tie portions each having a pair of spaced parallel slots therein extending transversely substantially therethrough, with the separated sections, so formed, of each tie connected by the adjacent base portions, corresponding slots in the respective tie portions being longitudinally aligned, and a rail member positioned in each series of longitudinally aligned slots, with the bottom edges of said rail members resting substantially on the respective base portions and supported therefrom, the width of said slots being such that the rail members are frictionally engaged by the adjacent edges of said tie sections.

4. In a miniature or toy railroad track, the combination of a tie strip of suitable electrical insulating material having a series of transverse corrugations therein, simulating spaced ties connected by base portions, said tie portions having downwardly diverging side walls, said tie portions each having a plurality of spaced parallel slots therein extending transversely thereto, corresponding slots in the respective tie portions being longitudinally aligned, and a rail member detachably positioned in each series of longitudinally aligned slots, the width of said slots being such that the rail members are frictionally engaged by said tie portions, said tie strip and rail members being flexible to permit curving thereof when desired, whereby the railroad track may be employed either as straight or curved track.

5. In a miniature or toy railroad track, the combination of a tie strip of suitable insulating electrical material, having a series of transverse corrugations therein, simulating spaced ties connected by base portions, said tie portions each having a plurality of spaced parallel slots therein extending transversely substantially therethrough, with the separated sections, so formed, of each tie connected by the adjacent base portions, corresponding slots in the respective tie portions being longitudinally aligned, and a rail member being positioned in each series of longitudinally aligned slots with the bottom edges of said rail members resting substantially on the respective base portions and supported therefrom.

6. In a miniature or toy railroad track, the combination of an elongated tie strip of suitable electrical insulating material having a series of spaced corrugations therein simulating a series of spaced transverse ties connected by intermediate base portions integrally formed therewith, said strip having a plurality of slots therein located in said ties, and arranged in a plurality of parallel series with the slots of each series located in different ties and longitudinally aligned with one another, and a rail member for each series of slots, each rail member having downwardly depending portions positioned in the respective slots of its series and engaged by the adjacent portions of the respective ties, the portions of the slotted ties intermediate the rail members being operative to define and maintain gauge alignment of such members.

7. As an article of manufacture, a tie strip for a miniature or toy railroad track having parallel rail members, comprising a thin strip of plastic material including a series of transverse corrugations therein simulating spaced ties formed with spaced slots, said slots adapted to frictionally and detachably receive the rail members.

8. As an article of manufacture, a tie strip for a miniature or toy railroad track having a rail member, comprising a relatively thin flexible strip of electrical insulating material including a series of transverse corrugation therein simulating spaced ties, said strip having a plurality of slots therein located in said ties and arranged in a pair of parallel series with the slots of each series located in different ties and longitudinally aligned with one another, each series being adapted to detachably receive portions of a respective rail member.

9. As an article of manufacture, a tie strip

for a miniature or toy railroad track having a flexible rail member, comprising a relatively thin strip of flexible material including a series of transverse corrugation therein simulating spaced ties having portions adapted to receive and frictionally engage the rail member, said corrugations having sufficient flexibility to permit bending of the strip in substantially the plane of said ties whereby the tie strip may be employed in either a straight or curved track.

HAROLD L. JOYCE.
